(57) **CLAIM**

The ornamental design for a water slide, as shown and described.

DESCRIPTION

FIG. 1 is an environmental right back perspective view of a water slide embodying my design.

FIG. 2 is a front elevational view thereof.

FIG. 3 is a left side elevational view thereof.

FIG. 4 is a right side elevational view thereof.

FIG. 5 is a rear elevational view thereof.

FIG. 6 is a top plan view thereof; and,

FIG. 7 is a bottom view thereof.

The broken lines showing in FIG. 7 form no part of the claimed design.

1 Claim, 6 Drawing Sheets
